(57) **CLAIM**

We claim the ornamental design for a trash receptacle loading ramp, as shown and described.

DESCRIPTION

FIG. 1 is a front perspective view of a trash receptacle loading ramp showing our new design;

FIG. 2 is another front perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines in the Figures are for environmental purposes only and form no part of the claimed design. The shading in the Figures shows contour and not surface ornamentation.
